SPOON OR SIMILAR ARTICLE OF FLATWARE

Robert King, Wallingford, Conn., assignor to World Tableware Corporation, Meriden, Conn., a corporation of Delaware

Filed Dec. 11, 1969, Ser. No. 20,460

Term of patent 14 years

Int. Cl. D7—03

U.S. Cl. D54—12

FIG. 1

FIG. 2

FIG. 3

FIG. 5

FIG. 6

FIG. 1 is a front elevational view of the spoon showing my new design;

FIG. 2 is a rear elevational view thereof;

FIG. 3 is a side elevational view thereof;

FIGS. 4—6 are sectional views taken on lines 4—4 through 6—6, respectively, of FIG. 1.

The design is intended for use on sets comprising spoons, forks, knives and similar articles of flatware. The essential features of my design for a spoon or similar article reside in the configuration of the handle in combination with the particular type of ornamentation as applied thereto.

I claim:

The ornamental design for a spoon or similar article of flatware, substantially as shown and described.
